PEGBOARD MOUNTED SUPPORT FOR AN ELECTRIC HAND DRILL

Albert J. Enckler, North Olmsted, Ohio, assignor to
A-B-L Associates, Inc., Cleveland, Ohio

Filed Sept. 11, 1975, Ser. No. 602,451

Term of patent 14 years

Int. Cl. D6—04

U.S. Cl. D6—114

FIG. 1 is a perspective view of a pegboard mounted support for an electric hand drill showing my new design; FIG. 2 is a front elevational view thereof; and FIG. 3 is a side elevational view thereof.

I claim:

The ornamental design for a pegboard mounted support for an electric hand drill, as shown and described.
